TRAFFIC SIGNAL

Edward P. Cheslock, Kennett Square, Pa., assignor to
E. W. Bliss Company, a corporation of Delaware

Filed Mar. 27, 1968, Ser. No. 11,153

Term of patent 14 years

Int. Cl. D29—99

U.S. Cl. D72—1

FIG. 1 is a perspective view of a plurality of traffic signals assembled to form a traffic control unit, the bottom two signals and the post being shown in broken lines for illustrative purposes only.

FIG. 2 is a perspective view of a traffic signal, showing my new design.

FIG. 3 is a front elevation view of the traffic signal.

FIG. 4 is a rear elevation view of the traffic signal.

FIG. 5 is a top plan view of the traffic signal.

The dominant features of my design reside in the portions shown in full lines.

The opposite side of the traffic signal shown in FIG. 2 is identical to the side shown.

I claim:

The ornamental design for a traffic signal, as shown and described.
